US0D1044598S

(12) **United States Design Patent** (10) Patent No.: **US D1,044,598 S**
(45) Date of Patent: ** Oct. 1, 2024

(54) **AUTOMOBILE**

- (71) Applicant: **LG ELECTRONICS INC.**, Seoul (KR)
- (72) Inventors: **Byunglok Jeon**, Seoul (KR); **Hansoo Kim**, Seoul (KR); **Sanghyeon Son**, Seoul (KR); **Inkoo Shim**, Seoul (KR); **Jinhee Kim**, Seoul (KR); **Byungkyu Kim**, Seoul (KR); **Sewon Chun**, Seoul (KR)
- (73) Assignee: **LG ELECTRONICS INC.**, Seoul (KR)
- (**) Term: **15 Years**

(21) Appl. No.: **35/520,887**

(22) Filed: **Apr. 8, 2024**

(80) **Hague Agreement Data**

Int. Filing Date: **Apr. 8, 2024**
Int. Reg. No.: **DM/236908**
Int. Reg. Date: **Apr. 8, 2024**
Int. Reg. Pub. Date: **May 17, 2024**

(30) **Foreign Application Priority Data**

Nov. 30, 2023 (KR) 30-2023-0048446
